UNITED STATES PATENT OFFICE.

CHARLES L. WHEELER, OF BURNS, NEW YORK.

DESIGN FOR A TAMPING-SHOVEL.

SPECIFICATION forming part of Design No. 31,473, dated August 29, 1899.

Application filed December 28, 1898. Serial No. 700,562. Term of patent 7 years.

To all whom it may concern:

Be it known that I, CHARLES L. WHEELER, a citizen of the United States, residing at Burns, in the county of Steuben and State of New York, have invented and produced a new and original Design for a Tamping-Shovel, of which the following is a specification.

The invention relates to a new and original design for tamping-shovels; and it has for its object to provide a design of this character which will be both useful and ornamental.

The leading feature of the design resides in a shovel having a flat rectangular blade provided at its inner end with a central concavo-convex raised portion and having an upturned transverse flange extending from the rear end of the raised portion and terminating at the side edges of the blade and having its upper edge arranged approximately in the same plane as the top of the raised portion and merging into the same.

In the drawings, Figure 1 is a perspective view of a tamping-shovel, showing my new and original design. Fig. 2 is a side view. Fig. 3 is a reverse plan view.

Referring to the drawings, I designates a rectangular shovel-blade of uniform thickness throughout, provided at its inner portion with a longitudinal concavo-convex portion 4, located at the rear end of the blade. The inner or rear end of the blade is provided

with a raised transverse flange disposed at right angles to the straight longitudinal side edges 3 of the blade and lying at opposite sides of the raised concavo-convex portion 4. The upper edge of the transverse flange is arranged in approximately the same plane as the top of the rear end of the concavo-convex portion, and it merges into the same.

Within the concavo-convex portion 4 is arranged a triangular head 5, formed at the terminal of an angle foot portion 6 of the straight handle-shank 7, and the said head tapers in width and in thickness. The lower face of the tapering head 5 is arranged in the same plane as the lower face of the shovel-blade and is flush with the same.

At the end opposite the terminal head 5 the handle-shank 7 is provided with an open triangular handle 8, having curved sides 9 and 10 provided with a cross-bar 10.

What I claim is—

The design for a tamping-shovel, herein shown and described.

In testimony that I claim the foregoing as my own I have hereto affixed my signature in the presence of two witnesses.

CHARLES L. WHEELER.
